REINFORCED INSULATOR PIN

Edward A. Mack, Huntington, W. Va., assignor
to Oliver Iron and Steel Corporation, Allegheny
County, Pa., a corporation of Pennsylvania

Application August 11, 1942, Serial No. 454,383

6 Claims. (Cl. 248—220.5)

This invention relates to insulator-mounting assemblies of the type including a pin mounted upon a cross arm and projecting upwardly to receive an internally socketed insulator for carrying electrical conductor wires.

One object of the invention is to provide a novel form of bracing for an insulator pin to enable such a pin adequately to resist the stresses imposed upon it in service by a conductor that is carried by an insulator mounted on the pin.

Another object is the provision of an assembly wherein the pin and bracing are in a novel way integrated into a unitary structure that is arranged to provide adequate bracing for the pin, and that is capable of simple and inexpensive manufacture, and facilitated service installation.

In the accompanying drawings,

Fig. I is a side elevation of my novel integrated assembly of insulator pin and the positioning and bracing structure therefor, showing the assembly on the cross arm of a pole.

Fig. II is a view showing the insulator pin positioning and bracing structure in plan and the insulator pin integrated therewith in cross section.

Fig. III is a similar view of the insulator positioning and bracing structure, but omitting the insulator pin and the means for integrating it with the said structure.

Fig. IV is a side elevation of the insulator pin positioning and bracing structure, omitting the insulator pin and the means integrating it with the positioning and bracing structure.

Fig. V is a front elevation of the structure shown in Fig. IV.

Describing the drawings in detail, the numeral 1 indicates a cross arm of standard type in pole-line use. The bracing for the insulator pin, such a pin being designated by reference numeral 2, is a generally triangular frame. The frame has a bottom arm 3 in the form of a base plate containing a centrally positioned pin-receiving hole 4, and side arms 5 and 6 that extend convergently upward from the bottom arm or plate 3. In order that arms 5 and 6 embracingly may engage insulator pin 2 projected through the pin hole 4, they extend convergently upward and inward to points sufficiently close to provide engagement upon opposite sides of the pin.

The uppermost portion of arms 5 and 6 and the flanges 5a and 6a extended upwardly from the upper margins of the arms are transversely formed to conform to the surface configuration of the pin and to provide a pin-receiving socket space 7 between them. The base 3 of the posi-

tioning and bracing structure is upwardly bowed transversely of the base between the edges 3a and 3b of the base.

The pin positioning and bracing structure is composed of a single piece of material, desirably 5 mild steel, punched and pressed to its desired form. When the insulator pin is integrated with its positioning and bracing structure in suitable manner such as that shown in the drawings and 10 to be described, the assembly is therefore one of extreme simplicity and sturdiness.

In making the integrated assembly shown in the drawings, the insulator pin 2 is passed through hole 4 in the base of the positioning and 15 bracing structure, and through the socket 7, between flanges 5a and 6a of the arms 5 and 6. Welds 8 and 9 are then made, firmly to integrate the insulator pin in the assembly. In the weld 8, the opposed edges 10 bordering the pin-receiving socket 7 provide anchorage for the weld metal which lies in the gaps 11 between them, and integrates the insulator pin with its positioning and bracing structure at two points circumferentially of the pin. The weld in both 20 peripherally spaced regions of the insulator pin being elongate axially of the pin and serving to bond together the two flanges 5a and 6a of the side arms as well as to bond the insulator pin to the flanges, the integration may be made with 25 great facility and effectiveness. Weld 9 integrates the insulator pin 2 with the base 3 of the positioning and bracing structure and the edges of the hole 3 through which the pin extends. This weld 9, by firmly engaging the structure relieves the weld 8 of forces tending to break it 30 which might result were the pin to remain loose in the hole 4, and supplements the weld 8 in preventing axial shifting of the pin. The welded integration of the triangular positioning and 35 bracing structure at both its base and its apex with the insulator pin, also causes the pin itself to reinforce that structure against distortion from its triangular form.

Insulator pin 2 extends upwardly beyond 40 flanges 5a and 6a of the positioning and bracing structure, and in its upward extension may carry insulator-engaging means such as the threaded lead thimble 12 shown in Fig. I. In its extension 13 downwardly beyond base 3 insulator pin 2 is threaded, and may as shown carry a washer 14 and nut 15 for clamping engagement of the assembly with the cross arm 1 of a pole.

The assembly may be mounted on the cross arm 1, as indicated in Fig. I, so that insulator pin 2 passes through a hole in the cross arm,

and the cross arm is clamped between washer and nut 14 and 15 on the pin shank and the base 3 of the frame structure. In mounting the assembly, the upwardly bowed contour of its base 3 permits the bracing structure to find a seat on the cross arm at the edges 3a and 3b on the opposite ends of the base, so that the assembly seats firmly in spite of irregularities in the surface of the cross arm. When so mounted the assembly resists turning movement of the insulator pin in all directions under the pull of a conductor wire passed around or attached to an insulator carried by the pin, because the triangular structure, or bracing element embracingly engages the insulator pin around the periphery of the pin, and because the integrated assembly bears by means of a base of relatively great area against the structure on which the assembly is mounted. Looseness of the insulator pin in the hole through the cross arm is thus wholly compensated. Also the triangular arrangement of the bracing frame and its welded integration gives an integrated structure of strength adequate to sustain severe stresses. The assembly, because of its bracing, has particularly great utility in locations in which a conductor wire is carried around a corner, so that the conductor wire pulls on the insulator pin from two relatively angular directions.

Substantial advantages of the described assembly thus derive both from the form of the bracing element and from its welded integration with the insulator pin. The advantages of strength and firm mounting have been described. Other advantages are to be found in its simplicity, in the ease with which it is manufactured, and in the fact that it is susceptible of complete factory fabrication ready for mounting and service. As will have been seen, the assembly may be quickly and easily mounted in the field.

It is to be understood that the physical embodiment of my invention herein shown and described is susceptible of modification in various particulars without departing from the principles of the invention, and the scope of my invention is therefore to be restricted only by limitations contained in the claims appended hereto.

I claim as my invention:

1. An integrated insulator pin assembly including an insulator pin, a one-piece bracing element having a pin-embracing base and arms extended convergently upward from said base and

shaped adjacent their upper ends cooperatively to form a pin-receiving socket space approximately surrounding the insulator pin, and means integrating the said insulator pin with said bracing element.

2. An integrated insulator pin assembly including an insulator pin, a bracing element having a pin-embracing base and arms extended convergently upward from said base cooperatively to form adjacent their upper ends a pin-receiving socket space, and means rigidly interconnecting the insulator pin with the said bracing structure at the pin-embracing base and at the pin-receiving socket thereof.

3. An integrated insulator pin assembly including a metallic insulator pin, a metallic bracing element having a pin-embracing base and arms extended convergently upward from said base and shaped adjacent their upper ends cooperatively to form a pin-receiving structure approximately surrounding the insulator pin, and bonding metal integrating the said insulator pin with both arms of the said bracing element at the pin-receiving structure formed thereby.

4. An integrated insulator pin assembly including a metallic insulator pin, a metallic bracing element having a pin-embracing base and arms extended convergently upward from said base cooperatively to form adjacent their upper ends a pin-receiving structure, bonding metal integrating the said insulator pin with both arms of the said bracing element at the pin-receiving structure formed thereby, and bonding metal integrating the insulator pin with the pin-embracing base of the bracing element.

5. A triangular bracing element for an insulator pin including a base plate perforate to embrace an insulator pin passed therethrough, arms extended convergently upward from said base, and extensions on said arms adjacent the upper ends thereof arranged to present opposed surfaces providing a pin-receiving socket approximately in line with the perforation in the base of the bracing element.

6. A triangular bracing element for an insulator pin including as a one-piece structure a pin-embracing base, arms extended convergently upward from said base, and flanges formed from the structure of said arms and extended axially of the bracing element to provide opposed extended surfaces forming a pin-receiving socket.

EDWARD A. MACK.
